WARPING MACHINE

Filed July 15, 1921 2 Sheets-Sheet 2

WITNESS

W. L. Bell.

INVENTOR,
Bernard Schram

BY John Edward,
ATTORNEY.

UNITED STATES PATENT OFFICE.

BERNARD SCHRAM, OF PATERSON, NEW JERSEY.

WARPING MACHINE.

Application filed July 15, 1921. Serial No. 434,840.

To all whom it may concern:

Be it known that I, BERNARD SCHRAM, a citizen of Austria, residing at Paterson, in the county of Passaic and State of New Jersey, have invented certain new and useful Improvements in Warping Machines, of which the following is a specification.

This invention relates to the operation of preparing a warp for a loom. According to a common method of preparing a warp for a loom groups of threads, called "sections," are wound one after another and side by side on the reel of a warping machine, thus to form the entire width of warp, and when this has been done all the sections are unwound at once from the reel onto the beam which goes into the loom as the warp-beam. The leading ends of all the warp-sections are placed, on starting to wind them on the reel, in registry with the same radial plane of the reel, and every section should be cut off at the same distance from the leading ends of the sections as every other, so that all the threads in the warp will be of identical length. In addition, at certain points in each section certain devices, as "cut-marks" to indicate lineal measurement or lease cords to maintain crosses in the sections, have to be inserted, and these in a perfectly prepared warp should register in all the sections so that those that correspond will all be in the same transverse line in the warp as a whole. Heretofore there has been no efficient means for indicating to the warper when the winding of a section should stop, the proper length having been wound on the reel, or when the devices, as cut-marks or lease cords, should be inserted; the ordinary means is a simple dial which is turned by the reel and with which a fixed pointer cooperates, but this is unreliable because the warper is apt, in attending to his numerous duties incident to the actual warping, to overlook the indicator thus afforded until the point predetermined on the dial has passed the pointer. My object is to provide a warping machine with an indicating means which by the closing of a circuit will cause an electric light to be lighted, the advantages of which are that it not only gives a signal but does so in a way to keep the signal operative for any desired period of time, as explained later, so that the warper cannot fail to observe it, and so as not to be a source of annoyance or con-

fusion to others, as other warpers serving neighboring machines.

In the drawings,

Figure 1 is a side elevation of a warping machine embodying my invention;

Figure 2 is a sectional view on line 2—2, Fig. 1;

Figure 3 is a plan, partly in section, of the parts cooperating in the closing of the circuit to give the signal;

Figure 4 is a section on line 4—4, Fig. 3;

Figures 5 and 6 are elevations of one of the circuit-closing clips; and

Figures 7 and 8 illustrate a modification.

The frame *a*, reel *b* journaled therein, reed-carriage *c* slideable transversely of the reel in the frame, the rotary member comprising a pulley *d* (suitably driven by a belt *e*) and a friction wheel *f* and journaled in the lever *g* fulcrumed in the frame, the treadle *h* for moving the said rotary member and so forcing the friction-wheel into peripheral contact with the driving band *i* of the reel, and the pitman *j* connecting said treadle and rotary member are or may be all substantially the same as in any warping machine. The weight of said rotary member, assisted by a spring *k* connecting the treadle with the frame, tends normally to hold it disengaged with the driving band of the reel, or in the position shown by full line by the drawing; but in order that the warper, instead of keeping the treadle depressed and so holding said member in contact with the driving band, may move about the machine to perform his duties while the reel is kept rotating I provide a prop *l* which may be interposed between a part of the frame and the treadle to hold the same down and said member engaged with the reel driving band, which prop may be knocked away when the reel is to be stopped so as to permit said member to fall and cease driving the reel.

The shaft *m* of the reel has a worm *n* on one end thereof and this meshes with the teeth of an index wheel *o* journaled in a bracket *p* upstanding from the frame. This wheel has a continuous series of equally spaced marks *q*, say one for each of its teeth. The wheel shown in Figs. 2, 3 and 4 is of the kind having a rim and spokes. Adapted to be attached to the rim are clips or contacts one of which is shown in Figs. 5 and 6 as consisting of a rebent piece *r* of flat metal, appearing substantially U-

shaped as viewed edgewise, and having in the plane and lateral of one of its legs an extension r' , the body part of the clip having one or more threaded holes s to receive 5 a set-screw u and the extension having a stud v projecting outwardly therefrom. This clip may be fitted over the inner perimeter of the rim of the wheel and secured to the latter by the set-screw, and the end of 10 its extension r' is so related to the stud v that if said end be placed in registry with one of the marks q the pin will be exactly centered between two teeth of the wheel. The extension is provided on the clip so that 15 its stud may be placed in registry with the space between two teeth notwithstanding the presence of the nearest spoke in the wheel.

On a part of the frame, as a bracket w 20 of metal, Figs. 2 to 4, one end of a horizontal strip x of fibre or other insulation is secured in parallel relation to the wheel o , the strip having a longitudinal slot y receiving a binding post z and a screw 2 which afford 25 its securing means; the slot permits the strip to be adjusted longitudinally. The other end of the strip is penetrated by the stem 3 which has a nut 4 screwed on it below the strip and above the strip a washer 5 and 30 also screwed on it a binding nut 6; when the nuts 4 and 6 are screwed up tight they bind a stop or stop plate 7, having its free end downturned, between nut 4 and the strip. On the lower end of the stem 3 is 35 freely pivoted as by being supported by the head $3'$ of the stem, lever 8 having its free end downturned and being normally held against the downturned end of said stop by a spring 9 connecting said 40 lever with the insulating strip. The downturned end of the lever stands in the path of movement of the studs v on the aforesaid contacts, so that when the wheel rotates in the direction of the arrow in Fig. 2 the studs 45 will successively obtain contact therewith, the lever moving aside until the stud in each case has passed and thereupon springing back against the stop. The lever thus forms a yielding terminal contact.

50 10 designates wiring, one end of which is grounded on the frame by being connected to the binding post z . It contains a light signal 11 and a source of energy 12. The other end of the wiring is connected to the 55 mounting for the yielding contact or lever as by being clamped between washer 5 and nut 6.

In Figs. 7 and 8 the form of the contacts r on the wheel is changed to suit the form of 60 the wheel, which is spokeless and is provided with a circumferential lateral rib 13 on which the contacts are clamped.

Before starting the warping operation the warper places the contacts r thereon in cer-

tain spacing, to wit, according to the points 65 where the signal is to be given for insertion of lease-cords or cut-marks or to denote the end of each section as it is wound. When each contact r approaches and engages a contact 8 the light will flash, remaining lighted 70 for more or less time until contact r clears contact 8. Seeing the light the warper displaces the prop l and stops the machine and having attended to the matter to which his 75 attention was called by the light starts the machine anew, whereupon the signal will be again given, of course, when the next contact r engages contact 8.

Having thus fully described my invention, 80 what I claim as new and desire to secure by Letters Patent is—

1. A warping machine including an open circuit having terminal contact means at the break therein and containing a signal and an energy source, revoluble means including 85 a reel on which to wind the warp, and a succession of circuit closing devices for said circuit clamping at intervals a peripheral portion of said revoluble means and slidably adjustable thereon independently of 90 each other in the direction in which it moves in the winding of the warp and also in the reverse direction, each of said devices being adapted during the movement of said movable means to wipe in contact with and 95 past the terminal contact means.

2. A warping machine including an electro-conductive frame, electro-conductive means movable in the frame in electro-conductive contact therewith and including a 100 reel on which to wind the warp, wiring grounded at one end on the frame and containing a signal and an energy source, and contacts one at the other end of the wiring and the other adjustable on said means in 105 the direction in which it moves in the winding of the warp and also reversely thereto, the latter contact being movable with said means into contact with the other contact.

3. A warping machine including an electro-conductive frame, electro-conductive means movable in the frame in electro-conductive contact therewith and including a 110 reel on which to wind the warp, an insulation piece, an electro-conductive device securing said piece to the frame, wiring having one end held by said device to said piece and containing a signal and an energy 115 source, and contacts one at the other end of the wiring and on said piece and the other adjustable on said means in the direction in which it moves in the winding of the warp and also reversely thereto, the latter contact being movable with said means into contact with the other contact.

120 In testimony whereof I affix my signature.

BERNARD SCHRAM.
